CARBURETOR VALVE

Huston D. Crippen, New York, N. Y.

Application October 31, 1932, Serial No. 640,566

2 Claims. (Cl. 251—145)

My invention relates to improvements in carbureting devices; particularly carburetors for supplying a motive agent to internal combustion engines.

5 An object of this invention is to provide an instrumentality capable of responding of itself to working conditions and the demand for power which the engine or motor must generate, and thereby effecting adjustments that enable the 10 performance of the engine to continue to be entirely satisfactory and/or the driving effect to be transmitted to the best advantage.

Another object of the invention is to provide suitable means for producing and supplying to 15 an internal combustion engine a motive agent varying in composition and amount according to requirements; said means being self-regulating and, when desired, united with one or more of the auxiliaries of the engine, or the connections 20 with the load to cause the engine to develop maximum power for a given amount of fuel, while consumption of said agent is reduced to a minimum.

A further object of the invention is to control 25 an internal combustion engine by means for carbureting air with liquid fuel to make a gaseous inflammable medium; introducing additional air in separate alterable amounts to said medium successively or simultaneously, and excluding the 30 additional air in the same way; and, when required, in synchronism with the fluctuations in the volume of additional air, actuating mechanism for governing the engine, or transmitting its power. Hence, with the engine working under 35 a certain load, and a change taking place in conditions, the alteration of the vacuum in the main intake of the engine and the rate or velocity of the intermingled air and fuel, due to the pumping effect of the pistons of the engine, will at one time cause a relatively small amount of fuel to be taken up to form the combustible motive agent; while at another time comparatively less air and more fuel will be commingled to enable 40 the engine to carry better an increase in load or respond properly to some other change in conditions of load or torque that render a relatively increased amount of fuel necessary; and said mechanism, if included, will then be correspondingly operated.

50 An additional object of the invention is to provide, to serve the purposes above mentioned, means for supplying a combustible motive agent to an internal combustion engine by utilizing, for adjusting or regulating quantities of additional air supplied to said agent, appliances which

are partly mechanical and partly independent of any mechanical connections; and which can function under the influence of the partial vacuum in the main intake of the engine, and the speed of flow of the air, to form the motive agent for 5 the power chambers of same.

Yet another object is to provide, in the practice of this invention as set forth, a lean and economical mixture whenever possible, and to convert such a mixture automatically into a richer 10 one for power purposes when needed; thus achieving a great saving in fuel, wear, repairs and general cost of operation of the engine.

A still further and very important object herein is to provide for feeding a motive agent to an 15 internal combustion engine by means which will draw liquid fuel from a reservoir ordinarily located below the level of said means without necessitating the use of auxiliary devices for the purpose.

20 It is also an object of the invention to provide a carburetor which has no inherent faults or structural defects to entail a loss of usefulness in any degree, or to bring about a derangement of function through wear or use, but which on 25 the contrary will retain its entire efficiency over extended periods of service. A further object of the invention is to provide a carbureting system of this superior design of simple construction and capable of being produced in large 30 quantities at comparatively low cost.

It is likewise an object of the invention to 35 provide a carburetor comprising parts that will automatically determine the composition of the mixture of air and fuel required for perfect combustion according to load; that will in and of itself generate and maintain a sufficient vacuum for effecting the delivery and the adequate vaporization of the fuel, and preserve the necessary ratio of air to fuel by preventing the admission, 40 to any considerable extent, of unregulated air and the uncontrolled excessive inflow of fuel and any accumulation of fuel within it; and by otherwise and completely safeguarding the vacuum within the range of practical conditions. In consequence, 45 the relative quantities of fuel and air going into the carburetor may be governed and the ingredients of the explosive charge supplied to the engine are thoroughly intermingled to a greater degree than heretofore possible. With a carburetor in which such conditions are enabled to persist, this mode of operation can always be obtained.

50 In all carburetors, and especially those without force pumps, vacuum tanks, float chambers 55

and other auxiliaries, the vacuum in the carburetor due to the suction of the engine, is the chief factor which ensures intake of fuel and air, and the vaporization and diffusion, through 5 the incoming air, of the former. For this result the continuation of the vacuum, and the velocity of inflow of air due thereto are essential; and if, from any cause, a decrease beyond permissible working variations in the vacuum occurs, the 10 serviceability of the device is at once seriously reduced. With a carburetor that has its parts incorrectly arranged, such a drop in vacuum, though not occurring at first, may take place after a time, when the movable elements of the 15 carburetor have been subjected to some measure of wear; creating, perhaps, new inlet passages and interfering with the action of the original channels of admission in the carburetor. For example, if the valves for the air and fuel or 20 any other parts are not properly located, the carburetor may gradually become so disordered in its operation that the fuel is not drawn in so readily; and is not vaporized and disseminated; and the air will enter in such a way that the 25 space or spaces where the vacuum should exist are brought nearer to atmospheric pressure, and the vacuum is wholly or partially destroyed. When such disturbances occur, the carburetor no longer supplies air and fuel in the proportion 30 demanded and does not fully vaporize the fuel; the control disappears and the power developed by the engine fails. The aim of this invention is to produce a carburetor so built that it will never undergo deterioration of this sort.

35 The nature and advantages of the invention are fully set forth in the following description, but I reserve the right to resort to changes in the shape, size and relative arrangement of parts and mode of proceeding without abandoning the 40 principle of the invention or going beyond the scope of the general meanings of the terms of the appended claims.

The drawings present several embodiments of my invention.

45 Figure 1 shows in side elevation an internal combustion engine with controlling apparatus therefor;

Figure 2 is a section through said apparatus on an enlarged scale;

50 Figure 3 is a section through another form of device for controlling the engine;

Figure 4 shows diagrammatically how the controlling device is connected to actuate mechanism associated with the engine, and

55 Figure 5 is a section and Figure 6 is a detail of a modification of what appears on Figure 3.

The same numerals identify the same parts throughout.

60 The invention is inherently self-regulating and responds of itself to changes in load, torque and other factors to vary the character of the motive agent continually according to working requirements; and thus controlling the engine is accomplished.

65 This application is a continuation in part of my companion case 423,309, filed January 23, 1930 for patent on carburetors.

The construction and mode of operation of my invention is clearly illustrated on the drawings, which show diagrammatically an internal combustion engine E to which is connected a carburettting device C, to which liquid fuel is conducted from a tank or reservoir T below the level of the carburetor to a point above the latter, 75 through a pipe 2a. The engine has power cham-

bers containing pistons one of which is indicated at P, and I is the main intake leading to the engine from the carburetor C. This carburetor will now be described to make clear how it operates in combination with the engine C, and 5 to set forth the entire invention.

As shown in Fig. 2 it comprises a hollow casing 1, with a fuel or gasoline inlet 2, through which pipe 2a delivers. In the sides of the casing at opposite points are air inlet apertures 3, and within the casing is a chamber 4, which opens through the top. The bottom of the casing, however, is closed. At its upper end the casing is flanged, to be affixed to the flanged end of the intake pipe I of the engine C. Carried by the lower end of the casing is a fuel or gasoline valve 5; and within the chamber 4 is a combined hollow valve and spray nozzle 6. This valve 6 is a controlling member for the air and fuel; and I provide the carburetor with valves for additional air, shown at 7 and 8. At the lower part of the casing 1 containing the fuel valve pin 5 is a bore or passage 9, which communicates with the chamber 4 and the gasoline inlet port 2; and passes through a central outside projection which is threaded inside to receive a headed sleeve nut 11. The metering pin 5 has a long tapering point on the inner end and is mounted in the opening or bore of the nut 11, which may carry a lock nut or gland 12; suitable packing being employed with these parts. On its outer end the pin 5 has a milled head 13 for turning to set the valve pin 5 in adjusted position. The nut 11 and the valve 5 can be taken out together. The stem 15 of the valve 6 projects down into the bore 9 and has a duct 16 which leads to the inside of the valve 6 at the upper end. Into the lower end of this duct the valve 5 always projects more or less so that the quantity of gasoline, or other hydrocarbon employed, entering this duct can be varied.

The valve 6 comprises a disk 17 with a conical rim, increasing in diameter towards the open end of the casing; and having thereon a head 18, with perforations 19 extending all around its side. The edge of the disk projects, forming a small annular ledge; and the duct 16 in the valve stem 15 communicates with the openings 19; the stem 15 being of course affixed to the head of the valve 6. Thus gasoline or other fuel entering the space 9 through the fuel inlet 2 can pass up in the channel 16 into valve 6 and out through the perforations 19. When the valve is in open position, air coming in through the apertures 3 takes up this fuel, vaporizing it as it issues from the perforations 19 in so many atomized fine jets or sprays, and making an excellent mixture of uniform composition which is dry and burns quickly, to give the engine the maximum power.

An arm 20 having a hub is affixed to a shaft 21, mounted to be able to turn in a transverse bore in the closed bottom of the casing 1. The casing 1 has slots 22 between the apertures 3, and the two ends of the shaft have fixed arms 23 on the outside of the carburetor. The arms 23 are pinned to links 24, and the upper ends of the links are united to the guide 25, which is affixed to the stem 15 in the casing 1, by screws 26 which pass through the slots 22.

In operation of the carburetor, the valve 5 is adjusted to admit enough gasoline for idling when the valve 6 is in relatively closed position. Gasoline flows up through the channel or passage 16 in the stem of this valve and out into the chamber 4 by way of the perforations 19. As the 75

- arms 23 are moved, the valve 6 opens more, lifting the stem 15 from the needle 5 to admit more gasoline from the inlet 2 to the duct 16. Hence more air and more fuel enter in predetermined rates, and the increased amount of air atomizes the additional fuel and delivers it from the chamber 4 into the intake I of the engine E. Enough air enters the inlet 3 to cause vaporization of whatever gasoline is admitted past the valve 6.
- 10 The angle or corner between the disk 17 and the head 18 makes a small space wherein the air flowing past the disk 17 creates a partial vacuum, drawing the fuel more readily out of the valve 6, and more quickly vaporizing it.
- 15 To mount the valves 7 and 8 for admitting additional air and making the operating of the carburetor more efficient and self-regulating, and controlling with reference to the engine, the casing has lateral extensions 27 at its upper end.
- 20 These extensions open downward, and each has secured thereto a hollow valve holder 28 with springs 29 and inlet openings 30 tending to shut these valves; but of unequal strength. The extensions communicate with the chamber 4 through ports 31 above the valve 6. In the extensions 27 between the air valves and the ports 31 are damper valves 32, turned by shafts 33 which project to the outside of the extensions and carry on their ends rigid arms 34. These arms are pinned to stems 35 which extend loosely through openings 36 in heads on the screws 26 outside of the casing. On the stems 35, which are threaded, are adjustable nuts 37. In the casing is an annular member 38, having a contracting conical inner surface 39, and a flaring conical inner surface 40, at the junction of which the valve 6 will be when in substantially closed position. Normally the dampers 32 are held closed by springs, 38', as in my prior application, Serial No. 356,685, filed April 20, 1929, which describes the carburetor fully, and are opened when the guide 25 is moved to lift the valve 6. The nuts 37 are set on the stems 35 to cause the dampers to be opened in succession; or at one time if desired. The stems 35 are yoke-shaped at the top, as disclosed in my aforesaid application, to span the lower sides of the extensions 27 and be more easily attached to the arms 34 on each shaft 33. Springs 29 may also, in some instances, be chosen so that their strength is equal.
- 50 With this type of carburetor the engine can be well supplied with motive agent and even automatically governed; for the carburetor is self-regulating and the controlling of the engine can be extended to the other accessories of same and even to the transmission devices and other apparatus if desired. In explanation of this the complete functioning of the carburetor will now be described.
- 60 When the valve 6 is fully open, the vacuum above the valve 6 created directly by the pumping action of the engine is negligible; but the velocity of the air flowing through the carburetor is quite high for a given speed; and if there were no supplementary and independent vacuum created by velocity of the air in the immediate vicinity of openings 19, the carburetor could not draw fuel up from the tank T.
- 65 The spring of the valve 7 may be assumed to be stronger than the spring of the valve 8; and the damper 32 adjacent the valve 7 is set to be opened first, because the nut 37 on the stem 35 thereof is screwed farther down towards the adjacent screw 26. Hence the valve 7 can open before the valve 8; and may remain open while the valve 8 is shut. Under some circumstances, the valve 8 may be open while the valve 7 is closed. With but one of these valves shut, a part only of the additional air is cut off, but some additional air is still supplied by the other. Two 5 of these valves give a fine, complete and more flexible governing action; for with a single auxiliary valve, conditions bringing about a complete closing would shut off the additional air entirely; and not just restrict the volume, as in the case 10 of two auxiliary valves, with one closed and the other able to remain open. Each of these valves can be timed to act sharply at the required instant. If, now a car driven by an engine having a carburetor as set forth herein is climbing a long 15 and steep grade with the valve 6 almost fully open or wide open; and if the grade is such that the car at the beginning attains a speed of 30-40 miles per hour with both valves 7 and 8 open; then, due to the increasing of the load and the 20 lessening of the momentum, the car will gradually slow down, and the speed of the engine drops. Therefore to some extent the velocity of the air flowing through the carburetor will diminish.
- 25 In consequence, the valve 7 having the stronger spring and therefore requiring a relatively greater air velocity to keep it open, will close first; cutting off the air flowing through it and the comparatively lean fuel mixture becomes richer through having a decreased proportion of air to 30 gasoline, and is more suitable for the development of increased power to meet the heavier load conditions imposed by travel up the hill. Also, the closing of the valve 7 tends to cause more air 35 to flow through the ports 3 and directly past the valve 6, and draw in more fuel through ports 19, thus helping a richer mixture to be produced. Increased power now tends to prevent further slowing up of the car. Therefore the valve 8, with a weaker spring, will remain open until either 40 the valve 6 is closed sufficiently to allow seating of the damper associated with valve 8 or until a still heavier load is encountered. Of course, if at any time the valve 6 is closed, both dampers 32 are shut and the valves 7 and 8 then close too; 45 and unless the dampers are opened, even though conditions are sufficient for the opening of the valves 7 and 8, the latter stay closed. In other words, a closed damper makes the associated auxiliary air valve inoperative and keeps it so until 50 its controlling damper is opened.
- To render the engine more sensitive when idling I adjust the parts so that the valve 7 is slightly open when the engine idles. This valve then determines to some extent the composition of 55 the mixture; and its spring will cause closing whenever the air pressure above it drops to a certain point.
- The spring of the valve 7 must be properly adjusted. If the valve 6 and the damper of the 60 valve 7 are opened quickly, too little spring tension will allow the valve 7 to snap open. Such action results in a temporarily "air-flooded" condition. But with the spring tension great enough the valve 7 will open more slowly and the too rapid 65 entrance of too much additional air is prevented; or the valve will delay opening or open and close again.
- Now if the car be started in low gear and the valve 6 be opened enough to give a speed of, say, 70 10 to 15 miles an hour, and the damper of the valve 7 is then slightly opened; then the vacuum in the intake pipe above the carburetor is quite pronounced, the engine speed is high, and the flow of air through the carburetor is sufficient to cause 75

the valve 7 to begin to lift. The other damper and valve 8 remain closed. Upon the gears being shifted from low to "second" and the valve 6 opened further, the damper associated with the valve 7 is opened further, and allows a proportionate increase in the opening of the valve 7. More air and fuel now enter and pass the valves 6 and 7 and a greater speed of engine and car results.

10 The valve 7 now stays open because the engine speed in second gear at 20-25 miles per hour for the car is not less than before with the engine in low gear, and is rising. Therefore, although the vacuum in the intake due to the increased opening of valve 6 for the desired 20-25 miles per hour is somewhat lower, the velocity of the moving air in conjunction with the lower vacuum is enough to keep the valve 7 from closing.

Suppose the car is now "in high", and goes faster till it is travelling at, say, thirty-five miles per hour. Valve 6 is now open more than before and so is the valve 7 and its damper 32. If now the valve 6 is still further opened, the other damper 32 will be opened, and at a 40 mile speed, say, the valve 8 can be lifted, so as to permit more additional air to enter the carburetor.

For more speed the valve 6 and both dampers 32 are opened still more. Hence the valves 7 and 8 can move further from their seats because of the resultant greater velocity of the air passing through the carburetor.

Should the load be now increased with the car in high gear, reducing the speed of car and engine, the valve 7 closes first because its spring is stronger; and will drop as soon as its spring can overbalance the energy of the air flowing past valve 7 and/or the vacuum past valve 6. The valve 8 may stay open.

If the car is traveling at 5-8-10-15 miles per hour and the valve 6 is opened suddenly to give quick acceleration, the damper 32 at the left may now be open; but with correspondingly slow engine speed there is little vacuum present and the velocity of air flow is not enough to keep open the valve 7. This valve then must close and the fuel mixture is enriched accordingly. The valve 7 can reopen when the engine speed increases, or the vacuum in the carburetor becomes great enough to make a leaner mixture again.

50 When the car is traveling at the rate of 50 miles per hour on a level road with both the valves 7 and 8 open, if the valve 6 is now closed sufficiently to permit the seating of the right hand damper 32, the air valve 8 would then, and 55 under this condition only, be the first of the two valves 7 and 8 to close.

The valves 7 and 8 can operate in relation to each other as follows: 1: Both valves open. 2: Valve 7 closed, valve 8 open. 3: Valve 7 open and 60 valve 8 closed. 4: Both valves closed.

Both valves can open when the valve 6 opens both dampers 32 and causes a relatively high speed of the engine.

65 The valve 7 may be closed and valve 8 open when the valve 6 is open far enough to cause both dampers 32 to be open. For example: When quick acceleration is attempted with valve 7 already open, as above stated, and the valve 7 cannot stay open, but the velocity of the air or 70 vacuum is still enough to open the valve 8. This action may occur under any conditions of medium load, or moderate speed, as when the car tries to tow another car; or when the car is traveling up a hill at moderate speed; or starts up the hill at 75 rather slow speed and the driver then tries to

increase the speed. The valve 8 only will be open whenever conditions are such that they will not overcome the spring of the valve 7, but are sufficient in degree to overcome the spring of the valve 8 and keep it open, when the damper of the valve 8 is open.

If conditions are such that the valve 6 is not open sufficiently far to open the damper of the valve 8, but does open the damper of the valve 7, the valve 7 may open while the valve 8 stays closed. Conditions sufficient to cause the opening of the valve 7 with its stronger spring, would cause the opening of the valve 8 unless the damper of the valve 8 is kept shut. It is possible to climb a grade with the valve 7 open, provided the grade is not steep enough to impose a load on the motor that would slow it down and make the valve 7 drop. Obviously the damper of the valve 8 must open before the valve 8 can lift, and as this damper can be set to commence to open at 35 to 40 miles per hour, all lower speeds, provided the valve 6 is not open enough to open the damper of the valve 8, result in the valve 7 only being used. Of course the figure of 35-40 miles per hour is stated by way of example only.

20 The two valves 7 and 8 can be closed at one time when the engine idles because the valve 6 then does not cause the opening of either damper. These valves will both be closed also when the inflowing air or vacuum has not force enough to overcome either the strong spring tension of the valve 7 or the weaker spring tension of the valve 8. For example: when the car is subjected to an increase of load, as upon a steep hill, causing a marked decrease in car and engine speed and a drop in air velocity and an insufficient vacuum.

25 The valves 7 and 8 can close independently of each other. The valve 7 is then the first to close when the closing is due to a drop in engine speed and vacuum and in velocity of air flow. But if the closing is caused by a reduction in the opening of the valve 6—thus allowing the damper of the valve 8 to close, the valve 8 would then close first.

30 Gasoline with two auxiliary air valves can be saved to a considerably greater extent than that obtainable with just one such valve. Conditions that would cause a single auxiliary air valve to close would not permit a reduction of the volume of additional air, but would stop the additional air entirely. Hence at times when a relatively lean mixture is needed it would not be furnished and gasoline would then be wasted for a short time. But with the two valves, conditions that would not permit the valve 7, for instance, with its stronger spring to be open would, however, be sufficient to keep open the other valve with its weaker spring, thereby letting in some additional air and affording a leaner mixture and saving gasoline until such time as the other valve has to close and furnish a richer mixture for the engine. Gasoline is also saved whenever the valve 8 only is opened and the mixture kept relatively lean by the additional air which the valve 8 supplies. And with both valves 7 and 8 open, the additional air will be sufficient to bring about a greater saving of fuel, because more additional air flows through these two valves than through either alone.

35 It is thus clear that the valves 7 and 8 operate automatically within certain limits; that is, with the valve 6 open and both dampers open, and without change of position of the valve 6 and dampers, the additional air valves can still move

independently of the dampers according to variations in conditions. They may, singly or together, move away from their seats, thus letting in more or less air, and producing a rich or lean mixture 5 as above outlined. It is well known that for high speeds, automobile mileage tends to drop and fuel consumption to increase but the above-described arrangement and mode of operation of the valves 7 and 8 tends to cure these defects and effect 10 the greatest saving of fuel by ensuring the leanest mixture at high and all other speeds; while at the same time enriching the mixture when load conditions require it.

The encountering of increased load conditions 15 automatically converts the economically lean mixture into a richer mixture more suitable to such load conditions and such richer mixture is automatically reconverted to the economical mixture with the lessening of load without changing 20 the position of valve 6.

An apparatus of this design will in effect yield 25 what may be called "cold carburetion". The fuel is thoroughly vaporized and the mixture of air and gas enters the engine fully intermingled and with the ratio of air to gas properly established. Hence combustion is rapid and thorough and the engine runs smoothly and evenly with jars and vibration eliminated, and undue wear prevented. Also fuel is saved, while the maximum efficiency 30 is produced under all conditions. I have even found that the heating of the engine is more easily controlled, for the fan can be disconnected and the engine permitted to run without the water pump going, if it has proper water jacketing, without reaching excessive temperature.

The carburetor in practice regulates itself, so far as the functioning of the valves 7 and 8 is concerned; and the engine, to that extent, is automatically controlled by the admission of a 40 richer or a leaner mixture according to working conditions, for all positions of the main valve 6. The usual connections are provided between the arm 20 and a hand lever on the steering wheel or elsewhere near the driver's seat; and the manipulation of this lever is accomplished in the same way as with a carburetor of ordinary design. The manual actuation is simply attended by the self-regulating function; which is; so to speak, superposed thereon.

50 This type of carburetor may not only be used as set forth, but also it may be united to exert its regulating influence on apparatus associated with the engine to widen the controlling effect. Figure 4, for instance, shows an ignition timer 55 41 having an arm 43 for advancing or retarding the spark. This arm is united to the stems 1a and 8a of the valves 7 and 8 by levers so that the spark is timed in accordance with conditions demanding that one or both or neither of the 60 valves 7 and 8 be open. The valve 7 is joined to a lever 43 and the valve 8 to a similar lever 44; these levers being illustrated as in line with each other and fulcrumed at their adjacent ends. 45 They are pinned to the valve stems near their pivot- 65 ed ends, and at their opposite ends they are pinned each to the slotted end of a floating lever 46, which is pinned at the middle to a link 47, which is attached to the timer arm 48. Obviously if both valves 7 and 8 open, the levers 43 70 and 44 will cause the maximum degree of movement of the floating lever 46 and the greatest advance of the spark. This is what is required, because when both valves 7 and 8 are open the engine speed will be highest. When one valve 7 75 or 8 is closed, however, the lever 46 will be shifted

around its end adjacent the other valve as a fulcrum to shift the link 47 and arm 48 somewhat to delay the spark; and this too is required because the engine speed will then be slackening. When both valves 7 and 8 are shut, the lever 46 5 is pushed at both ends to cause the link 47 to thrust the arm 48 and timer 41 to farthest retarding position.

This principle can also be utilized with other apparatus associated with an internal combustion engine, such as the change-speed gears, to shift the transmission connections automatically as working conditions demand.

The carburetor shown in Fig. 3 appears in horizontal section, and is preferably of the same design as set forth in my copending application Serial No. 423,309, filed January 25, 1930. It has a casing 1a which is in general L-shaped when seen in side elevation (or as viewed from either above or below as presented in Figure 3); and thus comprises a horizontal portion and a vertical portion, when the carburetor is mounted on an automobile engine. Hence the bore or chamber 4' will have a right-angled bend therein. The vertical portion of the chamber 4' which appears 15 in Figure 3 leads directly to the intake 1, to which the carburetor is attached; and the other portion, which will be horizontal opens through the end 122 of the carburetor. This end admits 20 air and receives a conduit to supply liquid fuel; and contains a valve and spray nozzle similar to 25 the nozzle described above, surrounded by a throttle ring similar to the ring 38, this nozzle and ring having relative movement to vary the quantity of air and fuel to be vaporized. Preferably 30 the nozzle is fixed and the ring is movable in this form. Said end also contains a valve pin to control the fuel mounted on the stem 5' which projects to the outside of the casing through the bend or elbow thereof and carries on its outer 35 end a head 49. Below this head is a shaft 50, mounted in bearings on the casing and this shaft has an operating arm 20a to turn same connected to any suitable means. On the shaft 40 are two fixed arms 49a to engage the head to enable the stem 5' to be adjusted. Normally a spring 5b on the stem 5' tends to move the fuel 45 valve pin to closed position.

On its top, the carburetor is provided with a pair of tubular outside extensions 81, one at each side of the vertical portion of the carburetor and substantially parallel to the horizontal portion. These extensions 81 are hollow as shown at 89, and communicate with the vertical part of the bore 4' through passages 100. At their outer 50 ends these extensions 81 carry auxiliary valves 111, which admit air to the extensions 81, as necessitated by working conditions. Air for vaporizing gasoline is taken in mainly through the inlet end 122 and the valves 111 will admit a 55 smaller or larger quantity of additional air as one or both of these valves are opened.

To enable the admission of the principal quantity of air and fuel to be regulated in the carburetor, two links 116 are connected to the throttle ring through slots (not shown) in the sides of the casing 1a, and are arranged to be actuated through a transverse shaft 51 having fixed arms 52 which are pinned at their lower ends to the links 116; as shown in my application Serial No. 423,309 aforesaid. The throw of these arms may be limited by providing on one side of the carburetor one or more projections 53 perforated and threaded to receive stop screws 54. On one end of the shaft 51 is an arm 56 to operate this shaft, 60 65 70 75 76

which passes through the casing near the open end 122, and projects at both sides, being mounted in bearings 57.

The outer ends of the extensions 81, which are 5 open, are internally threaded to receive threaded rings 58 carrying central bearings 59 secured by integral arms 60. Each bearing 59 receives a 10 slidable stem 61. These stems pass through openings in the disk valves 111 and have collars 10 62 for holding these valves against their seats while the outer ends of these stems have knobs 63.

On the top of the horizontal part of the carburetor is a bearing 64 in which is a transverse shaft 65 and the opposite ends of this shaft 15 carry bell crank levers 66. One arm of these levers has a screw 67 and lock-nut 68 to hold the screw in adjusted position. The screws 67 engage the knobs 63 and when the levers 66 are turned in the right direction, the stem 61 can 20 be forced inward. The screws 67 can be adjusted to move the stems 61 inward simultaneously, or in succession, at the right interval apart. The horizontal arms 69 of these bell crank levers are actuated by the upper ends of 25 the arms 52 as disclosed in my aforesaid application Serial No. 423,309.

The ends of extensions 81 adjacent to the vertical portion of the carburetor casing have the form of bearings 71 to receive pins 72 threaded at their outer ends for nuts 73. Within the extensions 81 these stems have smooth collars 74 in counter-bored recesses 75, while inward of the collars the pins 72 are threaded as shown at 76. These pins terminate in reduced shouldered extremities 77 in line with the stems 61; and between the stems 61 and pins 72 are springs 78. These springs bear against the collars 62 on the stems 61 and at their opposite ends they surround the extremities 77 on 40 the pins 72 and seat against the shoulders at the ends of the threaded portions 76 on the pins 72. The threaded portions 76 screw into the ends of thimbles 79, having collars 80 and springs 85 envelop the thimbles, seating against the collars 80 at one end and the valves 111 at 45 the other. At 82 is a projection on each of the thimbles 79 and at 83 are pins which are made fast inside the extensions and extend through apertures in the projections 82 so that the thimbles 79 cannot be turned. The outer ends of 50 the pins 72 may have kerfs to enable them to be turned by a tool. Rotation of these pins will thus by reason of the threaded portions 76 cause movement of the thimbles 79 towards or from the 55 valves 111 to adjust the springs 85; but the springs 78 will not be affected because no longitudinal movement of these pins occurs.

Normally the springs 78 press the collars 62 against the valves 111 to hold these valves shut. 60 Upon movement of the arm 56 to actuate the throttle ring (not shown) in casing 1a, however, the arms 52 turn the arms 69 of the bell cranks 66 upward to force the stems 61 inward, and move the collars 62 away from the valves 111. 65 These valves can then open against the springs 85 due to forces previously explained, when conditions demand. The mode of operation of these valves and the theory of their usefulness is the same as described above in connection with 70 Fig. 2.

The invention herein described involves the admission of gasoline through a variable and restricted inlet and it will be observed that the movable part for regulating the air, such as 75 the valve 6 in Fig. 2 and the same part in Fig. 3

(not shown), is so situated that the air encounters this member between the outlet ends of the jet openings 19 and the atmosphere. Hence the fuel is sprayed into the air stream at the point of greatest velocity of the air, and 5 the vaporization is most efficient for that reason. Accordingly, when the process of carburetion is performed and the additional air valves come 10 into play, automatic regulation changing the relative amounts of air and fuel in the mixture 10 is obtained; and this regulation is accomplished 15 in accordance with variations in load and torque, to control the engine, as the engine operates. In other words, changes take place in response to working conditions and the valves 1, 3 and 10 15 move to produce the desired results without any manipulation by the operator except to open the main air throttle as desired. Throughout the 20 operation an adequate vacuum is constantly present near the point of entrance of the fuel, either at the delivery ends of the jet openings or nearer to the fuel valve pin; though this vacuum may vary and drop considerably within the casing 25 of the carburetor towards the manifold I.

In the modification of Figs. 5 and 6 each valve 25 stem 61' is rigid with its valve 111. Each bell crank lever is actuated as before by one of the arms 52, and is notched at its upper end to receive the stem 61'. Each pin 72 has screw threaded 30 engagement with the casing 1a and at its inner end 77a it is smooth and headed over to retain its thimble 79 rotatably thereon. Hence these pins when rotated will actuate the thimbles to 35 adjust the springs 85, but the thimbles 79 as before are held against turning by the elements 35 83.

On the end of each stem 61' is a nut or nuts 89. Normally the levers 66 will press against these 40 nuts to hold the valves 111 closed. The levers are held in this position by springs 78a outside 45 of the extensions 81, pressing plungers 87 against rigid projections 86 on the levers. The springs 78a and plungers 87 are disposed in bores 88, formed in the exterior of the casing 1a, which is shaped for working to enable these bores to 45 be formed therein.

In operation, the levers 66 release the stems 61' when they are moved by the arms 52 against the force of the springs 78a. Then the valves 111 can open under air pressure against the 50 force of the springs 85.

I wish to point out further that the vaporization of the fuel really begins before it leaves the jet openings 19 in Fig. 2 and the corresponding 55 openings, not shown, of the constructions of Figs. 3 and 5. This is because the aspirating effect of the air as it passes the valve and spray nozzle 6, and the vacuum past this valve has a tendency to create a vacuum in the interior of the valve 6 and channel 16 and farther back along the line 60 of the pipe 2a. The fuel is thus partly vaporized when it issues from the valve and spray nozzle 6, and its vaporization is completed in the vacuum outside of this valve 6 towards the engine E.

While two additional air valves are preferred 65 the use of one such additional valve, under some conditions, will give regular results. Likewise, while springs of unequal strength tending to close 70 these valves are usually employed, these springs may be of equal strength in some instances. As clearly described above these air valves open when the vacuum above them is greatest and then move towards closed position when the vacuum diminishes.

I may also use an injector such as that indicated by 6 and 18 having a double ledge adjacent the jet openings instead of one ledge and the jet openings may be disposed adjacent either or both of these ledges.

Having described my invention, what I believe to be new and desire to secure and protect by Letters Patent of the United States is:—

1. A carburetor comprising a casing having an extension, a valve in said extension to admit air to the carburetor, a stem passing through the valve and having a collar in the extension to hold the valve shut, a spring engaging the collar to move the stem to valve-closing position, means

for actuating the stem to release the valve, a second spring to hold said valve shut and means for adjusting said second spring.

2. A carburetor comprising a casing having an extension, a valve in said extension to admit air to the carburetor, a stem passing through the valve and having a collar in the extension to hold the valve shut, a spring engaging the collar to move the stem to valve-closing position, means for actuating the stem to release the valve, and a second spring engaging said valve and tending to close same.

HUSTON D. CRIPPEN.
